POWER-OPERATED PORTABLE TOOL

William Henry Dean, Middleton Saint George,
Darlington, EnglandApplication December 17, 1949, Serial No. 133,569
In Great Britain December 23, 1948

4 Claims. (Cl. 125—33)

1

This invention relates to power-operated portable tools of the kind driven by resilient means working in conjunction with power-driven reciprocating mechanism provided apart from the tool and coupled thereto by a flexible drive.

The present invention has for its primary object to provide a working head having improved means for controlling the starting and stopping of the operative member of the head, said control means operating independently of the drive to the tool. Another object of the invention is to adapt the working head for use with a percussive operative member, such as a hammer for a rivet set, wall drill, scaling chisel or the like, or for use with a reciprocating operative member, such as a saw, shearing blade, punch or file. A further object of the invention is to improve the flexible drive to the working head whereby greater power may be transmitted to the operative member and the application of the tool to the work facilitated.

With the above and objects in view as will appear herein, my invention consists in the novel features of construction and the combination and arrangement of parts hereinafter described in detail and particularly set forth in the appended claims, reference being had to the accompanying drawings which illustrate portable tools embodying my invention and also the improved flexible connection between the reciprocating mechanism and the working head. In the drawings:

Figure 1 is a side elevation to a reduced scale of a portable tool in accordance with my invention, and

Figure 2 is an elevation looking on the left-hand end thereof.

Figure 3 is a sectional elevation of the working head of the tool fitted with a percussive operative member, and

Figures 4 and 5 are similar sections on the line IV—IV in Fig. 3 showing the control means in their obstructive and non-obstructive positions respectively.

Figure 6 is an elevation, partly in section, of a portion of the improved flexible drive, and

Figure 7 is an elevation, also partly in section, of the preferred power-driven reciprocating mechanism and the attachment of one end of the flexible drive thereto.

Figure 8 is a sectional elevation of the handle portion of a portable tool according to my invention and the attachment thereto of the other end of the flexible drive, and

Figure 9 is an elevation looking on the right-hand end of Fig. 8.

2

Figure 10 is a similar sectional elevation to Fig. 3 of the working head of the tool fitted with a reciprocating operative member, and

Figure 11 is a section on the line XI—XI in Fig. 10.

Referring first to Figs 1 to 5 of the drawings, the percussive tool therein illustrated has a working head 14 comprising a cylinder 15 provided with a flange 16 and united by a screw thread 17 to an extension 18 which is provided with a close-fitting cylindrical cap 19 encircled by a cover 20. The rear end of the cylinder 15 is embraced by the sleeve 21 of a handle 22, said sleeve being fitted onto said cylinder.

A piston 23 is reciprocated within the cylinder 15 by a flexible cable 24 having attached to it a ball-headed nipple 25 which is retained in a cavity in the piston by a ferrule 26 screwed into the rear end of the piston, which arrangement permits the cable to rotate independently of the piston, or vice versa. A helical compression spring 27 is interposed between the piston 23 and a washer 77 at the rear end of the handle (Fig. 8), the cable 24 extending through the spring.

The forward end 28 of the piston 23 has a marginal surface 29 which is not subjected to the wear on the piston resulting from its use as a hammer, and a control ring 30 is arranged 30 to co-act with said marginal surface. The ring is moved transversely in the working head between the forward end of the cylinder 15 and the opposite face of an internal recess 31 in its extension 18. The ring is interposed between a

35 pair of diametrically opposite balls 32, 33, the upper ball 32 being pressed downwards by a light spring 34 housed in a socket 35 partly in the extension 18 and partly in a finger piece 36 attached to the extension by a screw 37. The

40 finger piece engages a deep axial notch 38 in the cap 19 and prevents rotation of the latter. When the control ring 30 is in its obstructive position as shown in Figs. 3 and 4, the lower ball 33 rests in a socket 39 in the lower portion 45 of the cap 19. Movement of the cap to the right is limited by an external shoulder 40 around the rear end of the extension 18, and its movement to the left is limited by the head of a check screw 41 in said extension co-acting with

50 a slot 42 in the cap. An expanding split ring 43 may be provided in a groove around the extension to bear on the internal periphery of the cap and exert sufficient frictional pressure thereon to prevent the cap sliding freely on the extension.

The shank of a drill or chisel or other per-

cessive operative member with which my tool is used is inserted into a holder 44 which can slide in the extension 18. A grooved collar 45 tight on the holder bears against a shoulder 46 therearound, and a light helical spring 47 is provided between the collar and the bottom of a groove 48 in the end of the extension. The flanged end 49 of the cap 19 engages the collar 45 and limits the projection of the holder 44 under the pressure of the spring 47.

Fig. 7 shows, by way of example, a power-driven reciprocating mechanism consisting of a swash plate 50 mounted on the shaft of an electric motor 51. The ball 52 of the swash plate engages a socket 53 in the end of a hollow piston 54 working in a cylinder 55 secured by a nut 56 and a set screw 57 in the back plate 58 of the casing of the mechanism. The casing has a removable cover 59 provided with an inlet fitted with a screw plug 60 for admission of lubricating oil. A lubricating nipple 61 is fitted in the projecting end of the cylinder 55, and an extension 62 is screwed onto said end. The piston 54, which is reciprocated by the swash plate 50, is coupled to the piston 23 in the working head 14 by the flexible cable 24, the end of the cable in the piston 54 being provided with a ball-headed nipple 63 free to revolve in a ferrule 64 screwed into the end of said piston and to allow said ferrule to reciprocate when the piston 23 in the working head is held stationary by the control ring 30. The cable passes through the extension 62 into a flexible tube 65, the end of which is, as shown in Fig. 6, secured by a lock nut 66 screwed onto a threaded spigot 67 on a bush 68 free to revolve in a bearing 69 in the end of the extension thereby allowing the tube 65 to revolve relatively to the cable 24. The flexible tube is of stout construction, being composed of material capable of sustaining lengthwise compression, and is maintained partially charged with lubricant throughout its length by a supply of oil injected through the nipple 61. The cable 24 reciprocates in a sheath 70 the ends of which terminate in sockets within the ends of the tube 65. The other end of the flexible tube is, as shown in Fig. 8, secured by a lock nut 71 screwed onto one end of a threaded flanged spigot 72, the other end 73 of which is fitted with an adjusting nut 74 and is screwed into a flanged plug 75. A ball bearing 76 supporting the plug is inserted between the rear end of the sleeve 21 of the handle and the rear end of the cylinder 15. The rear end of the helical spring bears on a washer 77 abutting against an internal flange 78 at the rear end of the cylinder 15.

It will be seen that the leftward strokes of the piston 54 are transmitted by the cable 24 to the piston 23 in the working head 14 to move the latter piston to the right to compress the spring 27, and that, during the rightward strokes of the piston 54, the spring 27 provides the return stroke of the piston 23 while the cable 24 follows it up.

The control ring 30 normally engages the peripheral portion 29 of the piston 23 as shown in Figs. 3 and 4, being retained in this eccentric position by the spring 34. When the operative member in the holder 44 is pressed against a solid surface, the holder is moved to the right in the extension 18 and carries the collar 45 with it against the slight resistance of the spring 47. After a short initial movement, the collar engages the inwardly flanged end 49 of the cap 19 and slides it to the right causing the cam-

surfaced forward edge of the socket 39 in said cap to engage and raise the lower ball 33 and hence the control ring 30 against the pressure of the spring 34 into the position shown in Fig. 5 in which the ring is concentric with the body of the piston 23. The piston is then free to reciprocate through the ring under the action of the spring 27 and cable 24, the end 28 of the piston striking the opposed end 44a of the tool holder 10 44 and providing a hammer drive to the operative member therein. The cap 19 holds the ring in its concentric unobstructed position while the operative member in the tool holder 44 is pressed against the work. On said member being completely removed from the work, the piston, by impelling the holder 44 to the left, causes the collar 45 to pick up and return the cap 19 to its original position, thereby allowing the balls 32, 33 and the ring 30, under the pressure of the 15 spring 34, to return to the position shown in Figs. 3 and 4 in which the ring is eccentric to the piston 23 and the forward reciprocation of the latter is again obstructed. The spring 47 retains the holder 44 in the "off" position until the operative member therein is again forcibly pressed against its work. Surface friction between the cap 19 and the expanding split ring 43 in the extension 18 prevents the cap returning to the "off" position should there be any relaxation of 20 pressure during the application of said operative member to the work, the degree of lost motion allowed between the holder 44 and the cap 19 enables said member to vibrate without affecting the control means.

35 Normally the handle 22 is free to rotate relatively to the flanged plug 75 on the threaded spigot 73, but the handle can be locked to said plug by the engagement of the turned-up end 79 of an arm 80 with any one of a number of 40 notches 81 around the periphery of the plug. The arm 80 is fixed by a rivet 82 on the end of a threaded rod 83 in a hole 84 in the handle 22, the rod engaging an internally-threaded bush 85 in said hole and a spring 86 being inserted between the arm 80 and the bush 85. If the piston 23 requires to be adjusted, this can be effected by revolving the rod 83 by means of its milled head 87 to allow the spring 86 to push the arm 80 upwards until its end 79 engages one of the 50 notches 81 in the flange of the plug 75 whereupon the plug is locked to the handle 22 and the latter can be held to allow rotation of the adjusting nut 74 to travel the spigot 72, 73 on the cable. The provision of the ball bearing 76 permits the 55 handle 22 and working head 14 to revolve freely relatively to the flexible tube 65 and cable 24.

Figs. 10 and 11 illustrate a slightly modified construction wherein the working head 14a has a hollow piston 23a which receives the tang or 60 shank of a reciprocating operative member such as a saw, shearing blade, punch or file. The extension 18a of the cylinder 15a of the working head is provided with a conical-nosed cap 88 secured to it by a screw 89. The nose of the cap is 65 fitted with a band shield 90 and is apertured at 91 to form a guide for the operative member carried by the hollow piston 23a. The ball-headed nipple 25 of the cable 24 is introduced from the forward end of the piston and bears in a cup 93 in the rear end thereof. The control ring 30 contacts with a peripheral groove 29a around the piston 23a and is interposed between balls 32a and 33a, the upper ball being pressed downwards by a light spring 34a housed in a socket 35a in the 70 extension 18a. A rotatable cover 20a with a

milled circumference encircles the extension and retains the spring 34^a and lower ball 33^a in position. When the control ring 30 is in its normal position as shown in Figs. 10 and 11, its upper portion engages the groove 29^a in the piston 23^a and obstructs the reciprocation of the piston, the lower portion of the ball 33^a projecting through an aperture 94 in the cover 20^a. Finger pressure may be applied to the ball 33^a to raise the control ring against the pressure of the spring 34^a out of the groove in the piston into its non-obstructive position, whereupon the spring 27 and cable 24 co-operate to reciprocate the piston 23^a, but usually the control ring 30 is moved into its non-obstructive position by partially rotating the cover 20^a to move its aperture 94 around so that the cover maintains the control ring against the pressure of its spring.

It will be seen that, by this invention, I provide a working head provided either with a percussive operative member or with a reciprocating operative member, said working head in each case having an apertured control member comprising a resiliently mounted ring co-acting with a piston operated by a cable reciprocated within a tube and forming a flexible drive between said piston and the piston of a separated power-driven reciprocating mechanism. Either working head can be coupled to the reciprocating mechanism.

It is obvious that various modifications within the principle and scope of my invention may be made in the constructions shown in the drawings and particularly described herein.

What I claim and desire to secure by Letters Patent in the United States of America is:

1. A portable tool having a working head including a cylinder, a tool operating piston in said cylinder, a compression spring within the cylinder acting to urge the piston in one direction, a power-driven reciprocal mechanism driving said piston, a resiliently mounted transversely movable apertured control member disposed within the cylinder and normally yieldably held eccentric to the piston to prevent a full working stroke of the piston, means for moving said control member transversely into concentricity with the piston to permit the latter to operate through the aperture of the control member, said means including a casing carried by and movable relatively to the working head and disposed externally of said control member, and a member interposed between said casing and the external periphery of said control member coacting with the casing to transmit movement to the control member.

2. A portable tool having a working head including a cylinder, a tool operating piston in said cylinder, a compression spring within the cylinder acting to urge the piston in one direction, a power-driven reciprocatory mechanism driving said piston, the working head being provided with

a peripheral recess extending around the piston, a transversely movable control ring within the cylinder coaxing endwise with said recess, means for moving said control ring transversely into concentricity with the piston to permit the latter to operate through the control ring, said means including a casing carried by and movable relatively to the working head and disposed externally of the control ring, and a ball interposed between said casing and the external periphery of the control ring coaxing with said casing to transmit movement to the control ring, and a resiliently mounted ball interposed between said casing and the external periphery of the control ring and disposed opposite to said first mentioned ball, said resiliently mounted ball acting to normally yieldably hold the control ring eccentric to the piston to prevent a full working stroke of the same.

- 20 3. A portable tool having a working head including a cylinder, a tool operating piston in said cylinder, a compression spring within the cylinder acting to urge the piston in one direction, a power-driven reciprocatory mechanism driving said piston, the working head being provided with a peripheral recess extending around said piston, a resiliently mounted transversely movable apertured control member disposed within the cylinder and normally yieldably held eccentric to the piston to prevent a full working stroke of the piston, means for moving the control member into concentricity with the piston comprising a cap surrounding the forward end of said cylinder, a holder for a percussive operative member sliding in the forward end of the cylinder, a coupling between said holder and said cap to transmit the axial movement of the holder to said cap while permitting the holder to vibrate in operation, and means interposed between said cap and the external periphery of said control member for transmitting movement from the cap to the control member.

40 4. A portable tool as defined in claim 1 wherein the movable casing carried by the working head is rotatable to transmit movement to the means interposed between the casing and the external periphery of the control member to move the control member transversely into concentricity with the piston.

WILLIAM HENRY DEAN.
